UNITED STATES PATENT OFFICE.

JOHN F. O'CONNOR, OF CHICAGO, ILLINOIS, ASSIGNOR TO WILLIAM H. MINER, OF CHAZY, NEW YORK.

RAILWAY-CAR DRAFT-RIGGING.

1,293,619.

Specification of Letters Patent.

Patented Feb. 4, 1919.

Application filed August 25, 1916. Serial No. 116,771.

To all whom it may concern:

Be it known that I, JOHN F. O'CONNOR, a citizen of the United States, residing at Chicago, in the county of Cook and State of Illinois, have invented a certain new and useful Improvement in Railway - Car Draft - Rigging, of which the following is a full, clear, concise, and exact description, reference being had to the accompanying drawings, forming a part of this specification.

This invention relates to improvements in railway car draft riggings.

An object of the invention is to provide a draft rigging for cars of high capacity; wherein the necessity for stop castings is obviated; and wherein a novel type of yoke is provided, having the metal thereof distributed to the best advantage to withstand the heavy shocks in service.

In the drawing forming a part of this specification, Figure 1 is a longitudinal, vertical-section of a draft rigging showing my improvements in connection therewith. Fig. 2 is a longitudinal, horizontal sectional view 25 of the structure illustrated in Fig. 1 and taken on the line 2—2 thereof. And Fig. 3 is a transverse, vertical section taken substantially on the line 3—3 of Fig. 1.

In said drawing, 10—10 denote channel 30 center or draft sills of usual form, the same being each provided with five slots, 11, 12, 13, 14 and 15, all in horizontal alinement. The slots 11 are considerably elongated to accommodate the forward and rearward 35 movements of a coupler key 16 which connects the draw bar 17 with the improved yoke A, hereinafter described. The slots 12, 13, 14 and 15 accommodate the front follower 18, front inter-mediate follower 19, rear inter-mediate follower 20 and rear follower 21, respectively. Each of said followers consists of a plain flat plate mounted on edge and adapted to reciprocate back and forth in the usual manner, as will be under-

40 stood. The followers are prevented from accidental displacement by any suitable means, such as the cotters 22.

The yoke A, as shown, is in the form of a casting having an upper horizontal arm 23,

lower horizontal arm 24, rear connecting 50 wall 25, inter-mediate thimble or post 26 which is of H-shape in horizontal cross section, and a hooded forward end, the latter having side walls 27—27 slotted as indicated at 28 to receive the coupler key 16. As appears from Fig. 2, the rear end of the draw bar abuts the front follower 18 and is adapted to actuate the latter directly in buffing movement. The upper and lower horizontal arms of the yoke are connected by an integral, centrally located vertical web 29 (see Figs. 2 and 3), thus making the vertical section of the yoke of I form, as clearly shown in Fig. 3. The web 29 is cut away as indicated at 30, 31, 32 and 33 to accommodate 60 the followers 18, 19, 20, and 21, respectively. Mounted between the front and rear sets of tandem arranged followers, are horizontally disposed twin springs 34—34, thus providing a tandem twin gear. The parts of the 70 gear are supported by suitable means such as the saddle plates 35—35, the latter being detachably bolted to the lower flanges of the center sills.

In operation, in draft the yoke A is pulled 75 forwardly, thus moving the followers 19 and 21 forwardly and compressing the springs therebetween and the other followers 18 and 20, respectively. In buffing, the front follower 18 is directly actuated, as hereinbefore 80 pointed out and the yoke A is moved simultaneously with the draw bar through the instrumentality of the key 16, thereby actuating the follower 20 by means of the post or thimble 26.

From the preceding description, it will be seen that I have provided a gear of high capacity; which employs followers that may be readily and cheaply manufactured; which obviates the necessity of side castings; and 90 wherein the shocks are well distributed to the draft or center sills.

I claim:

As an article of manufacture, a yoke for railway draft rigging, said yoke comprising 95 a casting having upper and lower, flat, horizontally extending arms and integral, vertically extending, longitudinally spaced,

connecting sections, said yoke having also a centrally disposed, vertically extending integral web between said upper and lower horizontal arms, said web being cut away 5 adjacent said vertical connecting portions of the yoke to thereby accommodate movements of the followers with respect to the yoke,

said web being adapted to act as a spacer between horizontal twin arranged shock absorbing units.

10

In witness that I claim the foregoing I have hereunto subscribed my name this 22nd day of August, 1916.

JOHN F. O'CONNOR.
